UNITED STATES PATENT OFFICE.

NATHAN F. FRETTER, OF CLEVELAND, OHIO.

LATHE.

1,398,226.

Specification of Letters Patent. Patented Nov. 29, 1921.

Application filed December 5, 1917. Serial No. 205,485.

To all whom it may concern:

Be it known that I, NATHAN F. FRETTER, a citizen of the United States, residing at Cleveland, in the county of Cuyahoga and State of Ohio, have invented a certain new and useful Improvement in Lathes, of which the following is a full, clear, and exact description, reference being had to the accompanying drawings.

10 This invention relates to improvements in automatic machines of the class usually, and in the present instance, built in the form of turret lathes, and wherein the work is carried past a series of stations and temporarily 15 stopped at each for the purpose of subjecting it to the operation of one or a set of tools that contributes to the completion of the work.

The invention has for its objects the production of a machine of this character that is comparatively simple of construction; is compact, and therefore occupies only a limited amount of floor space; that requires but little attention; that is highly productive; 25 that is durable and substantial; and wherein all parts are easily accessible for purposes of inspection, replacement, or repair.

Other and more specific objects will become apparent as this description proceeds, 30 and the several objects are realized in the exemplification of my invention illustrated in the accompanying drawings, the present embodiment being designed to finish turn-buckles; and while I shall proceed to specifically describe this embodiment, it will be understood that I do not limit myself to the 35 structural details thereof further than is required by the terms of the claims annexed hereto.

40 In the drawings, Figure 1 represents a side elevation of the machine with parts broken away to better disclose certain structural details; Fig. 2 is a transverse section through the machine substantially on the line 2—2 of Fig. 1; Fig. 3 is a section on the line 3—3 of Fig. 1; Fig. 4 is a sectional detail on line 4—4 of Fig. 3; Fig. 5 (Sheet 1) is a sectional detail on the line 5—5 of Fig. 1; Fig. 6 (Sheet 2) a sectional detail on line 6—6 of Fig. 2; Fig. 7 is a perspective view of one of 50 the turn-buckle forgings which the present

embodiment of my invention is designed to finish; and Figs. 8, 9, and 10 illustrate the successive operations performed upon the forging by my machine.

55 Referring to the parts by reference numerals, 1 is a bed plate from the respective front and rear sides of which rise the standards 2 and 3, and a shaft 5 is journaled within the upper ends of these standards and carries, immediately inside the standard 2, a worm wheel 6 that is driven from a worm 7 secured to the central portion of a shaft 8 which extends transversely of the machine and is journaled, on each side of the worm, 60 in bearings 9 that extend inwardly from the standard 2, and near its ends in bearings 10 that are carried by standards 11 which rise from the bed plate adjacent each end of the transverse shaft. The left hand end of this 65 shaft, as viewed in Fig. 2, is equipped with pulleys 12 through which power is introduced into the machine from any suitable source.

70 Substantially midway between the standards 2 and 3, a frame 15 rises from the bed plate and, as shown, has formed integral with it, the lower half of a ring 16, while the upper half of the ring is made separate and secured to the lower half by bolts 17. A 75 turret 18 is loosely mounted upon the shaft 5 within the ring 16, and to the front end of its hub is secured a clutch member 19 for co-operation with a clutch member 20 that is splined to the shaft. The turret is in the 80 form of a drum, and secured to its periphery and spaced 90° apart thereabout are work 85 holders designated generally 25.

85 The work holders 25 are in the nature of clamps and each consists of a jaw 26 that 90 is secured, by screws 27, to the turret, and a jaw 28 that is movable toward and from the jaw 26, and is guided in its movement by a projection 29 of the jaw 26 which enters a recess in the other jaw. Springs 30 tend 95 to hold the jaws together, and the outer jaw 28 has ribs 31 which extend from its opposite ends for co-operation with the inturned lower ends of an inverted U-shaped plate 32 which is applied to the ring 16 at a point 100 which I shall, for convenience, term station A. This is the loading and unloading sta-

tion for the work holders, and the flanges of the plate 32, upon which the rails 31 of the work holders are adapted to ride, serve to open the work holders to permit of the 5 introduction of a new piece of work, and the ejection of a finished piece.

At what I shall term stations B, C and D, the ring 16 is provided with radially disposed tubular bosses 35 (shown in detail in 10 Fig. 4) which contain plungers 36, and in each instance the plunger 36 is impelled inward by a spring 37 confined between a flange of the plunger and a follower 38 that is adjustable within an end plate 39 which 15 closes the outer end of the boss, the plunger having an extension which is guided within a bore of the follower. The follower is adjustable for the obvious purpose of regulating the tension of the spring 37 to impose a greater or less pressure upon the 20 work holders which are adapted to ride beneath rollers 40, carried by the inner ends of the plungers. Each plunger is held against turning with respect to the ring 16 25 by means of a key 41 which occupies registering keyways in the plunger and adjacent portion of the ring. Hardened liners 43 are set within the opposed faces of the jaws of the work holder.

30 Rising from the bed plate and situated respectively to the front and rear of the frame 15, are housings 44 and 45 having bosses 46 through which the shaft 5 passes; and arms 47, braced by intermediate webs 48, radiate 35 from the bosses 46 and terminate at their outer ends in sleeves 49, there being but one exception, as will presently be explained.

The arms 47 are spaced 90° apart and their respective sleeves 49 are located at the 40 stations A, B, C and D. A plunger 50 is reciprocable in that sleeve 49 of the housing 44 which is located at station A, and is adapted to be moved within the sleeve by a cam 51, having a groove 52 within which 45 a pin 53 of the plunger extends. The cam is secured to the outer end of a shaft 55 that is journaled within bosses 56 of the arm. The inner end of this shaft has secured to it a beveled pinion 57 which is 50 driven from a beveled gear 58, secured to the shaft 5 forward of the housing 44. A like gear, bearing the same reference numeral, is fastened to the shaft 5 immediately to the rear of the housing 45. At station 55 A, a platform 60 is supported, in a horizontal position, from the adjacent arm of the housing 44, and is arranged to receive a turn-buckle T from a suitable chute 61 which will presently be described, the chute 60 depositing the turn buckle on the platform in alinement with both the plunger 50 and the work receiving recess of the work holder which is, at the time, at station A. As the plunger operates in a manner hereinafter 65 to be explained, it pushes a turn buckle from

the platform into the work holder, and through the intervention of this turn buckle, displaces the one just finished and causes it to be discharged into a chute 63, the upper end of which may be supported by 70 the adjacent arm 47 of the housing 45. This arm is broken away in Fig. 1, and its outer end is not equipped with a sleeve, as are the other arms, for its only function is to support the chute 63. The chute 63 75 extends outwardly and downwardly from one side of the machine and may discharge into a receiver 65.

At each of the stations B, C and D, the sleeves 49 of the opposed housings 44 and 45 are each interrupted intermediate of its ends by a transverse kerf which is occupied by a pulley 66 splined to a spindle 67 which is reciprocably and rotatably mounted within the sleeve. A yoke or member 68 is 80 swiveled to the forward end of each spindle, and its ends are connected, through flexible elements 69 that are guided over pulleys 70, to a weight 71 which tends to retract the spindle and retain its rear end in engagement with the periphery of a cam 73 that is carried at the outer end of a radially disposed shaft 74, journaled within bearings of the arm 47 and having a beveled pinion 75 secured to its inner end which meshes 95 with the adjacent beveled gear 58 of the shaft 5. Thus it will be seen that, as the shaft 5 rotates, the various cams 73 will be operated to reciprocate the spindles 67 within the sleeves 49, these spindles being 100 moved in opposition to the cams by the weights 71.

At station B, the adjacent ends of the opposed spindles 67 are equipped with facing cutters 80 for finishing the ends of the bosses 105 of the turn buckles as they are presented in operative relation to the facing cutters by the work holder, the effect of such operation being illustrated in Fig. 8. The spindles which carry the facing cutters are driven by 110 belts 81 that are guided over the pulleys 66, and over pulleys 82 that are secured to a shaft 83, supported along the left hand side of the machine in bracket 84 that extends from the housing 45, and in a standard 85, 115 located near the forward end of the machine. The forward end of the shaft 83 has secured to it a beveled pinion 86 that meshes with a similar pinion 87 on the drive shaft 8.

The shaft 83 is also equipped with pulleys 120 for driving, through the belts 90, the pulleys 66 that are splined to the spindles 67 at station C (Fig. 6), and which spindles carry drills 92 for boring the bosses of the turn-buckle, such operation being illustrated in 125 Fig. 9.

The opposed spindles at station D carry the taps 95 for threading the bores of the bosses of the turn-buckle, as shown in Fig. 10. The nature of these thread cutting tools 130

or taps makes it necessary to drive the spindle in one direction during the cutting operation, and in the opposite direction during the retraction of the spindle in order to 5 unscrew the taps from the threads which they have cut. This reversal in the rotation of the tap carrying spindles is accomplished through mechanism which I shall now describe. The right hand end of the drive 10 shaft 8 carries a bevel gear 100 which meshes with a similar gear 101, keyed to a comparatively short shaft 102 that is journaled, immediately to the rear of the gear 101, in a standard 103, and at its rear end in a bearing 15 104 carried by the adjacent housing 44. At about its middle, the shaft 102 has splined to it a double-cone clutch member 105 that is adapted to engage, when moved toward the right (in Fig. 1), with a clutch member 20 108 that is carried by a gear 109; and when moved toward the left, with a clutch member 110 that is carried by a gear 111. The gear 109 meshes with a gear 114 of similar size that is secured to a shaft 115, journaled 25 at its forward end in a boss 116 of the standard 2, and at its rear end in a boss 117 of the housing 45. The gear 111 is adapted to drive, through an idler gear 118, a gear 119 which corresponds in size to the gear 111, the 30 idler 118 being journaled upon a stud that is carried by the standard 103. It will be seen from this that, when the clutch member 105 is in either of its effective positions, the shaft 115 will be driven at the same speed as the 35 shaft 102, but in reverse directions accordingly as the clutch member 105 is shifted toward the right or left. Belts 120, which are guided over the pulleys 121 on the shaft 115 and over the pulleys 66 of the tap carrying spindles, transmit the power of said 40 shaft 115 to the spindles.

A shaft 125 that extends from front to rear of the machine and is in the horizontal plane of the shaft 115, has its front and rear 45 ends journaled, respectively, in suitable alining bearings of standard 2 and housing 45, that of the latter being indicated at 127 (Fig. 2), and said shaft is driven through a sprocket chain 128 embracing sprocket 50 wheels 130 on the shaft 5, and 131, on shaft 125. The upper forked end of a lever 133 embraces the groove of the clutch member 20, through which the rotation of the turret is effected, and the lower end of the lever 55 carries a roller 134 which traverses the face of a cam 135 that is fastened to the shaft 125. The cam is so designed as to cause the lever to be rocked at intervals to engage the clutch member 20 with the complementary 60 clutch member 19 of the turret to rotate the turret and thereby carry the work holders from station to station; and the turret is arrested in its rotary motion and positively positioned with the work holders properly 65 located at the various stations by the co-

operation of the nose of a lever 138 with recesses 139 that are formed in the rear face of the turret adjacent its periphery. The lever 138 is pivoted at 140 to a bracket 141 that extends rearwardly from the frame 15, and 70 the lever is rocked in a direction to project its nose into the recesses by means of a spring 143 that has one of its ends connected to the lever and its opposite end attached to the aforesaid frame. The lever is rocked in the 75 opposite direction by a cam 145, secured to the shaft 125, and engaging a roller 146 that is journaled upon the lower end of the lever.

A hopper 150, supported a suitable distance above the machine, is adapted to receive a quantity of turn-buckle forgings; and as the forgings tumble down into the reduced lower end 151 of the hopper they are picked up by fingers 152 of a drum 153, as the drum is rotated, the fingers being designed to engage between the side bars of the turn-buckles. The drum 153 is mounted on a shaft 154, which may be supported in suitable hangers, and is driven through a belt 155, trained over a pulley 156 of the drum 90 and over a pulley 157 that is carried by the shaft 5, to the rear of a sprocket wheel 130. The forgings are picked up by the fingers 152 and carried over and deposited in a suitable slide 160 which directs them to the 95 upper end of the chute 61, the same consisting of opposed side rails between which the forgings descend to the platform 60.

Operation: The groove in the cam 51 is so shaped that, as the cam rotates, it will project the plunger 50 forwardly a sufficient distance to push a turn-buckle forging from the platform 60 into the adjacent work-holder and, by means of this forging, eject the one previously finished by the machine, 100 the latter being conveyed by the chute 63 to the receiver 65. The plunger 50 is then withdrawn from the work-holder sufficiently to escape interference with any moving parts of the turret, and it remains over the 110 platform 60 and beneath the chute 61 to sustain succeeding forgings until it is subsequently withdrawn for the purpose of projecting another forging into the next work-holder. After a forging has thus been deposited in a work-holder, the cam 145 rocks the lever 138 to withdraw the nose of the lever from a recess of the turret, unlocking the turret, and the cam 135 rocks the lever 133 to engage the clutch member 20 with the 115 clutch member 19 and retains the clutch engaged long enough to carry the turret through 90°, or until the previous work-holder is brought to station B, when the lever 138 rides from the effective portion of 120 the cam 145, allowing the spring 143 to swing the lever 138 in a direction to project its nose into the adjacent recess of the turret. As soon as the work-holder moves from station A, the upper jaw thereof is released 125 130

by the member 32, allowing the springs 30 to set the jaws and clamp the forging between them. During the facing operation, as well as succeeding operations, this clamping action is enhanced by the spring actuated plungers 36. After the facing operation has been completed, the turret is again rotated through 90° to present the forging to the drills 92 at station C, and upon completion of the drilling operation, the turret is actuated to carry the forging to station D, where the taps are projected into and withdrawn from the bores of the bosses, threading them and thus completing the work. The finished work is then returned to station A where it is ejected by a succeeding piece.

Having thus described my invention, what I claim is:—

20 1. In apparatus of the character set forth, the combination of opposed supporting structures, a series of spindles rotatably and reciprocably sustained by each structure, the spindles of each series being disposed about a circle, means for driving the spindles, a cam for moving each spindle longitudinally, a shaft carrying each cam and radially disposed with respect to the circular disposition of the spindles, a shaft parallel to the spindles and situated centrally thereof, gearing through which the latter shaft drives each of the former shafts, and a tool carried by each spindle and opposed to the tool of the other and between and in operative relation to which tools a piece of work is adapted to be supported.

25 2. In apparatus of the character set forth, the combination of sets of opposed tools disposed about a circle, means for driving the tools, mechanism for moving the tools toward and from each other, a rotatable carrier adapted to support a piece of work and move the same between and in operative relation to the opposed tools of the various sets, and a common actuator passing through the axis of the carrier for operating the carrier and the aforesaid mechanism.

30 3. In apparatus of the character set forth, the combination of opposed tools, means for driving the tools, mechanism for moving each tool toward and from the other, a carrier for moving a piece of work between and in operative relation to the tools, a common actuator for the carrier and the aforesaid mechanisms and whereon the carrier is supported, said actuator being continually active, means for intermittently coupling said actuator to the carrier, and operative connections between the actuator and the coupling means.

35 4. In apparatus of the character set forth, the combination of opposed tools, means for driving the tools, mechanism for moving each tool toward and from the other, a carrier for moving a piece of work between and

in operative relation to the tools, a common actuator for the carrier and the aforesaid mechanisms, said actuator being continually active, means for intermittently coupling said actuator to the carrier, means for locking the carrier when the work is in operative relation to the tools, and connections between the actuator and the coupling and locking means whereby said means are operated by the actuator.

5. In apparatus of the character set forth, the combination of a plurality of work holders, a carrier for moving said work holder through an orbit, tools arranged at stations about the orbit for operating upon work sustained by the work holders, means for operating the tools, a common actuator for the means of the various tools, means for intermittently coupling the carrier to said actuator, and connections between the actuator and the coupling means whereby said means is operated by the actuator.

6. In apparatus of the character set forth, the combination of a plurality of work holders, a carrier for moving said work holders through an orbit, tools arranged at stations about the orbit for operating upon work sustained by the work holders, means for operating the tools, a common actuator for the means of the various tools, means for intermittently coupling the carrier to said actuator, means for locking the carrier with the work in operative relation to the tools, and connections between the actuator and the coupling and locking means whereby said means are operated by the actuator.

7. In apparatus of the character set forth, the combination of a plurality of work holders, a carrier for moving said holders through an orbit, tools disposed about the orbit for operating upon the work, means situated at a loading station for depositing work within the holders, mechanism for operating said means and each of the aforesaid tools, a common actuator for the mechanisms of the loading means and the various tools, means for intermittently coupling the carrier to the actuator, and connections between the actuator and the coupling means whereby said means is operated thereby.

8. In apparatus of the character set forth, the combination of a shaft, means for continually driving said shaft, a turret loosely mounted upon said shaft, a clutch for coupling the turret to the shaft, work holders carried by the turret, tools disposed about the circular orbit of the work holders, operative connections between the shaft and said tools, and connections between the said shaft and the aforesaid clutch and through which the clutch is intermittently actuated to couple the turret to the shaft.

9. In apparatus of the character set forth, the combination of a shaft; means for continually driving the shaft; a turret loosely

mounted upon the shaft; work holders carried by the turret; a clutch for coupling the turret to the shaft; tools disposed at intervals about the orbit of the work holders; 5 means for locking the turret with the work holders disposed in operative relation to the tools; and connections between the shaft, the locking means, and the aforesaid clutch, whereby the locking means and clutch are 10 operated from the shaft.

10. In apparatus of the character set forth, the combination of a shaft; means for continually driving the shaft; a turret loosely mounted upon the shaft; a clutch for coupling the turret to the shaft; a plurality of opening-and-closing work holders sustained by the turret; means situated at a point about the orbit of the work holders for cooperation with the work holders thereby to 15 open them; means for introducing a piece of work into each holder when under the influence of the aforesaid opening means; tools disposed about the orbit of the work holders; means for retaining the work holders 20 in closed condition when in operative relation to each tool; operative connection between the various tools and the shaft; means for locking the turret with the word holders in operative relation to the tools; and connections between the shaft, said locking 25 means, and the clutch, whereby the locking means and clutch are actuated from the shaft.

11. In apparatus of the character set forth, the combination of a plurality of opening-and-closing work holders, a carrier for moving said work holders through a given course, means disposed along said course for opening the work holders when 30 the work holders are presented in operative relation to said means, means for introducing a piece of work into the work holders when open, tools disposed at intervals along the course, means for maintaining the work 35 holders in closed condition when in operative relation to the tools, means for actuating the tools, and means for moving the carrier.

12. In apparatus of the character set forth, the combination of a shaft, means for continually driving said shaft, a turret 40 mounted loosely upon said shaft, a clutch for coupling the turret to the shaft, a plurality of work holders carried by the turret, tools disposed at intervals about the orbit 45 of the work holders, means for actuating said tools, a device for locking the turret with the work holders in operative relation to the tools, means for actuating the aforesaid clutch, a second shaft, driving connections between the first and second shafts, and cams carried by the second shaft for coöperation 50 with the locking device and the clutch actuating means.

13. In apparatus of the character set forth, the combination of a drive shaft, a 55

shaft continually driven therefrom, a turret loosely mounted on the driven shaft, a clutch for coupling the turret to the driven shaft, a plurality of work holders carried by the turret, tools disposed at intervals about the orbit of the work holders, driving connections between the drive shaft and said tools, the driving connections between the drive shaft and certain of said tools including reversing mechanism, a device for locking the turret with the work holders in operative relation to the tools, means for actuating the clutch, a cam shaft, driving connections between the driven shaft and cam shaft, and cams carried by the last mentioned shaft for actuating the locking device, the clutch actuating means, and the aforesaid reversing mechanism. 75

14. In mechanism of the character set forth, the combination of opening-and-closing work holders, a carrier for said work holders, means for opening the work holders when the work holders are presented in operative relation thereto, a work support sustained along the path of movement of the work holders and adjacent the opening means, means for depositing work upon said support, a pusher arranged to move the work from said support to the holder, and mechanism for reciprocating said pusher. 85

15. In apparatus of the character set forth, the combination of a shaft, a work carrier revoluble thereon, mechanism for directly coupling the work carrier to the shaft, tools disposed at intervals about the course 90 of the work carrier, and connections between the shaft and the aforesaid mechanism whereby said mechanism is operated from the shaft.

16. In apparatus of the character set forth, the combination of a shaft, a work carrier revoluble thereon, mechanism for coupling the work carrier to the shaft, tools disposed at intervals about the course of the work carrier, means for locking the carrier 100 when in a given relation to the tools, and connections between the shaft, the locking means and the aforesaid mechanism, whereby said locking means and mechanism are operated from the shaft. 110

17. In apparatus of the character set forth, the combination of sets of opposed tools, said sets being disposed about a circle, means for driving the tools, a cam for moving each tool toward the opposed tool of its 120 respective set, shafts carrying said cams, said shafts being radially disposed with respect to the circular disposition of the sets of tools, a central shaft, transmission mechanism interposed between the central shaft 125 and the cam shafts, and means for supporting a piece of work between and in operative relation to opposed tools.

18. In apparatus of the character set forth, the combination of sets of opposed 130

tools, said sets being disposed about a circle with respect to the center of which the tools are fixed against angular movement, means located between the sets of tools and movable about said circle for presenting a piece of work successively to the corresponding tools of the opposed sets, means for advanc-

ing the opposed tools of each set toward each other, and a centrally situated actuating member for operating the aforesaid means of all the tools.

In testimony whereof, I hereunto affix my signature.

NATHAN F. FRETTER.
